UNITED STATES PATENT OFFICE.

GEORG FRANK, OF GRANGER, WASHINGTON.

REVERSIBLE ENVELOP.

1,202,373.

Specification of Letters Patent. Patented Oct. 24, 1916.

Application filed February 9, 1916. Serial No. 77,228.

To all whom it may concern:

Be it known that I, GEORG FRANK, a citizen of the United States, residing at Granger, in the county of Yakima and State of Washington, have invented certain new and useful Improvements in Reversible Envelops, of which the following is a specification, reference being had to the accompanying drawings.

10 This invention relates to new and useful improvements in paper receptacles and more particularly to a reversible envelop and the primary object of the invention is to provide an envelop of this class which may be 15 readily reversed and used as a return envelop.

A further object of the invention resides in providing an envelop of improved and simple construction, inexpensive to manufacture and very useful in operation.

With these and other objects in view, the invention consists in the novel features of construction, combination and arrangement of parts as will be hereinafter referred to 25 and more particularly pointed out in the specification and claim.

In the accompanying drawing forming a part of this application, Figure 1 is a plan view of the blank in its out-spread position. 30 Fig. 2 is a similar view thereof as it is initially folded and sealed. Fig. 3 is a similar view showing the same folded and sealed in position for returning. Fig. 4 is a section as seen on line 4—4, of Fig. 2; and Fig. 5 35 is a similar view as seen on line 5—5, of Fig. 3.

In describing my invention, I shall refer to the drawing in which similar reference characters designate corresponding parts 40 throughout the several views and in which 1 indicates a blank or sheet of paper designed to form my improved envelop, which consists of a central section 2, inclosed by the dotted lines, as indicated at 3 and formed 45 on the one edge thereof, the bottom edge in the present instance, is a flap 4 which is substantially of the same size as the section 2. This flap 4 is designed to form the rear wall of the envelop, the same being bent 50 with respect to the section 2, along the dotted line indicated therebetween and formed on the side edges of the central section 2, are the side flaps 5, and formed on each of said side flaps, as a continuation thereof, are the 55 extensions or auxiliary side flaps 6. These extensions or auxiliary side flaps 6 are bend- able with respect to the main side flaps 5, along the dotted lines indicated as 7 and the one face of each extension or auxiliary flap 6 and the adjacent outer edges of the 60 main side flaps 5, are gummed or covered with an adhesive of any preferred type, as clearly shown in Fig. 1 of the drawing.

Formed on the edge of the central section 2, opposite that on which the flap 4 is 65 formed, is a top or closing flap 8 which is bendable with respect to the section 2 along the dotted lines therebetween and this flap is preferably of larger size than the side flaps 5 and designed for engagement with 70 the outer face of the rear wall or bottom flap 4. Formed on, and designed to form a continuation of said flap 8, is the extension or auxiliary closing flap 9 which is bendable with respect to said flap 8 along the dotted line indicated as 10. This auxiliary closing flap 9 is the same with respect to the flap 8 as are the extensions or auxiliary flaps 6 with respect to the side flaps 5 75 and the one face of said extension 9 and the adjacent face of the flap 8 along the outer edges thereof is gummed or covered with an adhesive, as clearly shown in Fig. 1.

In Fig. 1 of the drawing, I have shown a plan view of the blank in its outspread position and disclosing the front face of the central section or front wall of the envelop prior to the formation thereof in its original position and, in describing the manner in which the envelop is folded, I will, for convenience, refer particularly to this view. In the formation of the envelop, the rear wall or bottom flap 4 is first folded inwardly 80 against the rear face of the front wall or central section 2. The outer or auxiliary side flaps or extensions 6 are folded along the dotted lines 7, rearwardly against the rear or under faces of the side flaps 6, whereupon said side flaps are then bent inwardly 85 along the dotted lines between the same and the central section 2, for contact with the outer face of the rear wall of the bottom flap 4. Such disposition of the flaps will dispose the auxiliary flaps or extensions 6 inwardly 90 with respect to the rear wall and the gummed faces thereof which are disposed inwardly, are moistened and secured to the outer face of said rear wall 4. The envelop is then 95 ready for use and the name and address of the addressee is then placed on the outer face 100 of the front wall or section 2 of the envelop, as shown in Fig. 1 of the drawing. As this 105 110

envelop is particularly adapted for use as a return envelop, the name and address of the addresser is preferably provided on the under face of this central or front wall section 2 of the envelop prior to the folding thereof. This, I have shown somewhat in dotted lines in Fig. 1 of the drawing. The letter or other communication may be placed in the envelop, as desired, and in sealing the 5 same, the extension or auxiliary closing flap 9 is bent inwardly against the under face of the closing flap 8, along the dotted line 10 and the complete closing flap 8 bent inwardly along the dotted line between the 10 same and the central section 2, against the outer face of the lower flap or rear wall 4. This positions the gummed face of the extension or auxiliary flap 9 against the outer face of the rear wall, and this gummed face 15 is moistened and properly engaged with the rear wall, thus completely sealing the envelop.

In folding the auxiliary flaps of the side and closing flaps of the device in place and sealing the same, I provide preferably a flexible connection 11 which is disposed at the junctions of the auxiliary flaps and the main flaps, as indicated clearly in Fig. 2 of the drawing. The free ends of the flexible 20 connection are permitted to project from the lower edges of the side flaps, as clearly shown in Fig. 2 and when it is desired to open the envelop, it is only necessary to draw upwardly upon the ends of said connection, as shown in dotted lines in said Fig. 35 1, which operation will sever the main side and closing flaps from the extension or auxiliary side and closing flaps. This will entirely open the envelop and permit the 40 auxiliary flaps to be retained in secured positions against the outer face of the rear wall 4. In using the same envelops for return purposes, it is only necessary then to bend this rear wall 5 backwardly over the 45 opposite face of the front wall 2 and likewise bend the side flaps 5 backwardly against the outer face of the rear wall 4 which, in this instance, is the opposite face, to the face which was previously considered the outer 50 face of said rear wall. This will dispose the gummed edges of the side flaps inwardly

and the same may be moistened and secured to the rear wall. The envelop is then ready for return use and after the return communication has been inserted therein, the 55 closing flap 8 is then bent backwardly over the then outer face of the rear wall 4 and this also positions the gummed edges of the closing flap inwardly and the same may be moistened and properly sealed, thus completely sealing the envelop for return use. 60

From the foregoing it will be seen that I have provided a simple, inexpensive and efficient means for carrying out the objects of the invention and while I have particularly 65 described the elements best adapted to perform the functions set forth, it is obvious that various changes in form, proportion and in the minor details of construction may be resorted to without departing from the spirit 70 or sacrificing any of the principles of the invention.

Having thus described this invention, what I claim is:

A reversible envelop of the class described 75 comprising a central section, a rear wall flap formed on the lower edge of said section and foldable in both directions with respect thereto, side flaps formed on the side edges of said central section, also foldable in both 80 directions with respect thereto, auxiliary side flaps formed on the outer edges of the first mentioned side flaps to form continuations of the latter, said auxiliary side flaps being foldable inwardly with respect to the main side flaps, a closing flap formed on the upper edge of the central section and foldable in both directions with respect thereto, and an auxiliary closing flap formed on the outer 85 edge of the first mentioned closing flap and foldable inwardly with respect thereto, the outer faces of said auxiliary side flaps and the adjacent faces of the main side flaps and the like faces of the closing flap and auxiliary flap being gummed. 90

In testimony whereof I hereunto affix my signature in the presence of two witnesses.

GEORG FRANK.
